UNITED STATES PATENT OFFICE.

CHARLES E. DREW, OF WOONSOCKET, RHODE ISLAND, ASSIGNOR OF ONE-HALF TO GEORGE H. BAKER, OF SAME PLACE.

UNDERSHIRT.

SPECIFICATION forming part of Letters Patent No. 495,316, dated April 11, 1893.

Application filed September 8, 1892. Serial No. 445,334. (No model.)

To all whom it may concern:

Be it known that I, CHARLES E. DREW, of Woonsocket, in the county of Providence and State of Rhode Island, have invented a new and useful Improvement in Undershirts and Like Garments, of which the following is a specification, reference being had to the accompanying drawing, in which I have shown a perspective view of the improved garment.

10 The invention relates more especially to undershirts although it is of course applicable to garments of various kinds; and has for its object to construct a garment which will readily conform itself to the body of the wearer, and have a better appearance than like garments heretofore made and possesses other advantages presently to be ascertained.

15 The improved undershirt consists of a body portion, arm pieces, and a yoke, the body portion being cut with gores to which portions of the arm pieces and the yoke are secured, the arm pieces and yoke projecting above the gores and secured together above the gores, forming shoulder straps. As usually constructed the straps of the body portion were continued upwardly to meet across the top of the shoulders where a seam joined the meeting ends; the yoke and arm portions being then attached entirely to the edges of the garment 20 and having no other function than to ornament the article. This latter arrangement resulted in a doubling up of the shoulder pieces owing to their width and caused great discomfort owing to the uncomfortable seam.

In the drawing *a* is the body portion of the 35 garment cut with the gores *b* and *c*. The yoke may consist of a suitable edging or lace susceptible of various ornamentation, which is attached to the body of the garment at *e'* and to the inner edges of the gores, but having 40 the portions *e''* extending beyond the gores forming loops for the shoulder straps. The ends of the yoke meet in the rear of the garment so that no seam encumbers the shoulders. To the outer edges of the gores the arm 45 portions *d* are attached having the extended portion *d'* projecting above the gores and secured to the yoke at *d''*. The meeting edges of these arm pieces *d* are joined under the arms, so that no transverse seam occurs across 50 the shoulders.

I claim—

The improved undershirt made up of a body portion, gores on the upper part of the garment, a yoke secured to the body portion and 55 to the inner edges of the gores and projecting above the gores, arm pieces secured to the outer edges of the gores and projecting above the gores, the arm pieces and yoke being secured together above the gores as and for the 60 purposes set forth.

CHARLES E. DREW.
